CLAIM

The ornamental design for a flexible shaft machine as shown and described.

DESCRIPTION

1. Flexible shaft machine

1.1 : Front

1.2 : Rear

1.3 : Left side

1.4 : Right side

1.5 : Top

1.6 : Bottom

1.7 : Perspective

The broken lines in the drawings depict portions of the flexible shaft machine that form no part of the claimed design.

Flexible shaft machine is used for non-destructive flexible pipe dredging for all kinds of sewers, drains, sewage pipes, water pipes, heating pipes, milk pipes, oil pipes and other blockages, to ensure that the pipeline is clear.
